UNITED STATES PATENT OFFICE.

GEORGE COOK, OF BUFFALO, NEW YORK.

BOILER.

Application filed March 17, 1920. Serial No. 366,481.

To all whom it may concern:

Be it known that I, GEORGE COOK, a citizen of the United States, residing at Buffalo, in the county of Erie and State of New York, have invented a new and useful Boiler, of which the following is a specification.

This invention relates to boilers of upright type which are provided with water tubes.

The general object of the invention is to provide an improved boiler construction and one which insures rapid heating of the water and the delivery of dry steam to the engine.

Another object is to provide a boiler which may be readily assembled or dismantled.

A further object is to provide a boiler whose parts are readily cleaned.

The invention will be best understood from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient features of the invention as expressed in the appended claims.

In the drawings, Fig. 1 is an elevation of an embodiment of the invention.

Fig. 2 is a vertical section of the same.

Fig. 3 is a horizontal section of the same.

Fig. 4 is a detail, showing the manner in which the inner shell and the plate covering the opening in the outer shell are secured together.

Fig. 5 is a detail, showing the means for holding the cupped fittings to the upper ends of the tubes.

Fig. 6 is a plan view of one of the fittings.

The numeral 10 represents the outer shell of the improved boiler, which shell, as shown in Fig. 3, is substantially square in cross section having rounded corners. The upper end of the shell 10 has an annular top plate 11 secured thereto with a circular flange 12. A steam dome, including a cylindrical wall 13 and a top plate 14, is se-

cured to the annular plate 11 by means passing through the flange 12. The top plate 14 of the steam dome has an annular flange 15 and a flue 16 passes through the top plate 14, being secured to the steam dome by means of elements running through the annular flange 15.

The lower end of the outer shell 10 has a base plate 17 secured thereto and to the inner shell of the boiler, the inner and outer shells and the plates 11 and 17 forming a water compartment of the boiler. A plate 18 provides an ash pit at the lower end of the inner shell and has an opening 19 which may be closed by the usual form of door. A collar 20 is secured to the inner and outer shells of the boiler by means of flanges 20^a (see Fig. 2). This collar provides a passageway for the fuel and the opening is closed by the usual type of fire door (not shown).

Access may be had to the water compartment of the boiler for cleaning by means of hand holes of the usual type closed by caps 21 or the like (see Fig. 1). Such holes are provided near the bottom of the water compartment and pass through the outer shell of the boiler. In order to get at the water tubes, which are carried by the inner shell of the boiler, the outer shell is provided with a number of openings 22, there being one opening for each side of the outer shell. These openings have an area slightly less than the area of that portion of the inner shell defined by the tube ends. The relative position of one of the passageways 22 and the tube ends is indicated in dotted lines in Fig. 2. These passageways 22 are normally closed by plates 23, studs 24 holding the plates upon the outer face of the shell 10. The outer shell is provided with an edging 26 which runs about the perimeter of the plate 23, and a packing 25 is interposed between the plate 23 and the shell. This packing is held and prevented from bulging outwardly by means of the edging 26. This arrangement of the edging and packing makes a watertight joint where the plates are connected to the outer shell and yet permits ready removal of the plates when the tubes are to be cleaned.

Stay bolts 43 connect the inner shell with the plates 23. As seen in Fig. 4, these stay bolts are held to the plates 23 by means of

2
screw threaded collars or sleeves 44. The outer ends of the bolts 43 have heads which engage with the sleeves 44, and caps 45 are threaded upon those portions of the sleeves 5 44 which extend without the plates 23. A construction similar to this has been described in my co-pending application Serial No. 241,591.

The inner and outer shells of the boiler 10 may be braced by additional stay bolts 42 of conventional form, or these additional stay bolts may be similar to the bolts 43 already described. The outer shell is preferably braced at the corners by elements 27 15 and 28, as seen in Fig. 2.

Secured within the steam dome by the same elements 29 which hold the steam dome upon the upper end of the boiler is a baffle 30, including a cylindrical wall, which is 20 spaced from the walls of the flue and of the dome and a lower annular wall 31 which, with the walls 30 and 13, forms a steam compartment 32. The upper end of the baffle 30 is spaced from the top plate 14 of the 25 steam dome, as shown. The steam baffle, the dome and the flue are coaxial with each other. The wall 13 of the dome is provided with a number of openings near its lower end, which openings are closed by the plugs 33. The purpose of these plugs is to permit 30 ready cleaning of the steam compartment 32. A pipe line 32^a, provided with a valve, is connected to the steam compartment and provides means by which the same may be 35 drained at desired intervals.

A pipe 34 is connected with the steam space by means of a suitable fitting, a valve 35 being provided so that the flow of steam 40 through said pipe may be cut off when desired. Another pipe 36 is secured to the same fitting and is in turn provided with a valve 37. In order to distinguish between these 45 two pipes, the pipe 34 will here be referred to as a main steam line and the pipe 36 as the emergency steam line. It will be clear that if there is anything wrong with the main steam line, by closing the valve 35, the emergency steam line may be employed.

The main steam line passes upwardly 50 from its connection with the steam dome and is run into the flue 16, where it is formed into one or more coils 38 comprising a super-heater extending longitudinally of the flue. At the lower end of these coils a pipe 39 of 55 smaller dimensions than the pipe of the main steam line is connected. This pipe 39 passes upwardly through the flue and out through the wall of the same, being provided outside of the flue with a valve 40. This 60 pipe 39 constitutes a blow-off pipe by means of which water accumulated in the coil 38 may be blown off, thus insuring dry steam. The main steam line continues outwardly 65 through the wall of the flue and onto the engine, as indicated at 38^a.

The inner shell 41 of the boiler has a cross section similar to that of the outer shell and carries a plurality of rows of water tubes 46, 47, 48, 49. The tubes of each row incline upwardly and slant out of vertical 70 plane. The tubes are connected with the two opposite faces of the square inner shell, adjacent rows, as 48 and 49, being connected with separate faces and thus crossing each other. The tubes of every second row, as 75 47 and 49, are inclined with respect to vertical planes in different directions so as to cross each other also. The tube ends of every second row are staggered with respect to each other as seen in Fig. 2. There the 80 tubes of the row 47 are shown inclining toward the back and slanting to the left, while the tubes of row 47 slant upwardly but incline to the right. The rows 46 and 48 are placed in a similar relation.

In order to insure more rapid circulation of the water in the tubes than the upward incline of the tubes would cause, fittings 50, comprising cup-like elements, are secured to the upper ends of each of the tubes. 90 These fittings give a pronounced circulation to the water as it leaves the tubes and enters the water space between the shells. For clearness in illustration, only a few of the tubes of the boiler have been shown as provided with these cup fittings 50. It will be understood that the upper ends of all of the tubes are to have these cup fittings mounted thereon. As seen in Figs. 5 and 6, a dovetail element 52 is provided upon the outer 95 end of each tube and provides means by which the cup fittings may be removably held upon the tubes. The cup fittings have tongues 51 adapted to slide upon the dovetail connection 52 and hold the fittings securely in place, though permitting of ready removal when the tubes are to be cleaned.

The arrangement of the water tubes and the disposition of the accelerating means on the upper ends of each tube are in staggered 110 relation, and the accelerating means on the ends of each tube of alternate rows provides a construction whereby fluid emanating from the tubes of one row may travel in parallel relation to the streams of fluid 115 issuing from the tubes of alternate rows for a portion of their upward travel in the boiler without interfering with each other. Furthermore, the accelerating means on the end of each tube protects issuing streams from rising fluid which has been delayed in its 120 upward progress. It is a well known fact that fluids of lower temperature do not mix readily with fluids of higher temperatures, and where it is attempted to cause a rapid 125 mixture of the fluids of different temperatures, considerable resistance will be experienced, but in the present device, since the various streams of fluids of different temperatures are caused to travel in parallel 130

relation for a portion of their upward movement and then gradually mix, the resistance of the flow of fluid in the boiler will be greatly diminished.

5 In the present boiler extraordinary provision has been made for insuring a supply of dry steam. Furthermore, means are provided whereby all parts of the boiler may be reached for cleaning. The relatively 10 small size of the openings 22 saves boiler plate and adds to the strength of the boiler. As the dotted lines of Fig. 2 indicate, when cleaning the boiler tubes not all of the same can be reached from one side of the boiler. 15 In order to clean two rows, such as rows 47 and 49, one may run the boiler tube cleaner through all the tubes except the extreme right-hand tube of row 49 and through all the tubes of row 47 except the 20 extreme left-hand tube. These two tubes, because of their inclination, the one to the left and the other to the right, are readily cleaned from the opposite side of the boiler. If the boiler shells were cylindrical, as is 25 common, tubes arranged like those which have been described could not be employed. The square shape of the inner shell permits of ready removal of the tubes when desired and gives a large area exposed to the hot 30 gases and flames of the fire. I desire to use any size and number of tubes in the inner shell which may seem desirable and any number of rows of such tubes. The boiler is a strong one, is readily assembled or dis- 35 mantled and the parts thereof may be easily removed for repair. The edging does not

merely hold the packing in place, but considerably strengthens the boiler plate of the outer shell where it is cut away, besides helping to secure the plate which covers 40 the cutaway section.

What is claimed is:

1. An upright boiler of the water-tube type comprising an outer shell, an inner shell having a fire box therein, a flue connected to the top of the inner shell, a steam dome on the top of the outer shell surrounding the flue, a baffle coaxially mounted in the steam dome having an integral flange presenting a downwardly bent portion adjacent to the lower edge of said dome, and means to secure said flange and the lower edge of said dome to said outer shell, whereby said integral flange forms the bottom of the steam space between said baffle and 50 said dome.

2. In an upright boiler, an outer shell, an inner shell, a flue connected to the top of the inner shell and leading upwardly, a steam dome made fast to the top of the 60 outer shell, the flue passing through the top of the dome, a cylindrical baffle in the dome and coaxial with both the flue and the dome, said cylindrical baffle being connected with the dome where it is joined to the outer shell, 65 the same elements being used to unite the three named parts.

In testimony, that I claim the foregoing as my own, I have hereto affixed my signature.

GEORGE COOK.
